(57) **CLAIM**

The ornamental design for a lanyard, as shown and described.

DESCRIPTION

FIG. 1 is a perspective view of a lanyard showing my new design in a first state;

FIG. 2 is a front elevational view thereof;

FIG. 3 is a rear elevational view thereof;

FIG. 4 is an enlarged left side elevational view thereof;

FIG. 5 is an enlarged right side elevational view thereof;

FIG. 6 is a top plan view thereof;

FIG. 7 is a bottom plan view thereof;

FIG. 8 is a perspective view of the lanyard in a second state;

FIG. 9 is a perspective view of the lanyard shown in use, with the lanyard in a third state;

FIG. 10 is an enlarged view of a circled portion 10 of FIG. 1;

FIG. 11 is an enlarged view of a circled portion 11 of FIG. 6; and,

FIG. 12 is an enlarged view of a circled portion 12 of FIG. 8.

The broken lines in the drawing depict portions of the lanyard that form no part of the claimed design.

The break lines are shown to indicate that no particular length is claimed, and any portion shown in between the breaks forms no part of the claimed design.
